UNITED STATES PATENT OFFICE.

JOHN S. JORDAN AND JAMES E. ELLER, OF INDIANAPOLIS, INDIANA; SAID
ELLER ASSIGNOR TO WILLIAM MCGINNIS, OF SAME PLACE.

FOLDING STEP.

SPECIFICATION forming part of Letters Patent No. 446,385, dated February 10, 1891.

Application filed December 17, 1890. Serial No. 375,031. (No model.)

To all whom it may concern:

Be it known that we, JOHN S. JORDAN and JAMES E. ELLER, of Indianapolis, county of Marion, and State of Indiana, have invented 5 certain new and useful Improvements in Folding Steps; and we do hereby declare that the following is a full, clear, and exact description thereof, reference being had to the accompanying drawings, in which like letters refer 10 to like parts.

Our invention relates to the construction of folding steps or ladders, and will be understood from the following description.

In the drawings, Figure 1 represents a perspective view of our device attached to a car-platform. Fig. 2 is a side elevation, the lower section of the steps being folded back. Fig. 3 is a similar view of the parts open in line. Fig. 4 is a perspective view on the opposite side of Fig. 3, showing the arrangement of the locking-latch on that side.

In detail our device consists of an upper section 1, having lower section 2, connected by hinges 3, the lower section adapted to be 25 folded up behind or dropped down in line with the upper section in the manner herein-after described. Steps are connected to the side pieces in the usual manner. A lever 4 is pivoted at 5 to one side of the frame and is 30 provided with a pin 6, which works in a slot 7, formed in a curved brace 8, which is pivoted at 9 to an auxiliary lever 10, having a slot 11, and a pin 12 passes through this slot into the side of the lower section 2 of the 35 frame.

13 is a curved brace pivoted at 14 to the piece 10, and at the opposite end at 15 to the lever 4.

16 is a spring-plate provided with a handle 40 17 and beneath with a locking-pin 18, which enters a hole 24 in the lever 4. The slot 11 in the piece 10 has an offset at its upper end to permit the lateral movement of the lever 10 beneath the head of the pin 12. The sides of 45 the steps are connected by a rod 19, which passes through them, and its ends are squared, one to enter the inner side of the slotted plate 10 at 19 and the other entering at 20 the plate 21 on the opposite side. This plate has an 50 offset slot 22, through which passes a pin

23, so that the movement of the lever 4 on the one side is transferred through the rod 19 to the plate 21 on the opposite side, and a similar movement of this plate with regard to the pin 23 takes place, so that the parts 55 will lock on both sides by one and the same movement.

The lever 4 is intended to control the folding mechanism, and the operator taking hold of its handle pulls it over until it takes the 60 position shown in Fig. 2, and the lower section 2 is folded behind and under the upper section 1 in the manner shown, and if the device be applied to a car, as shown in Figs. 1 and 3, when the train stops at an ordinary 65 platform the lower foldable section 2 of the steps will not be needed and will remain drawn up behind, as shown in Fig. 2; but if the car should stop beyond the platform, making the step down too great, the operator 70 takes hold of the handle of the lever 4, pulls it up, and this throws the lower section 2 out in the position shown in Fig. 1, making an additional step for the foot of the passenger.

When the parts are in the position shown 75 in Figs. 1 and 3, the curved braces 8 and 13 operate as locking-braces, and the more pressure that is put upon the step the tighter the device is locked in place. The offsets of the slots 11 and 12 allow a relative movement of 80 the locking-pins 12 and 23 in these offsets. We say "relative" because these pins themselves do not move; but the braces do, so that the pins are thrown to one side and at an angle to the main part of the slot, and this locks 85 the parts in position.

Our device is easily constructed and applied and is entirely controlled by a single lever. It is adapted for car-platforms, steps, and ladders of various kinds. 90

What we claim as our invention, and desire to secure by Letters Patent, is the following:

1. A folding step or ladder comprising two tubular sections hinged together in the rear, a lever pivoted to the upper section, a corresponding lever slotted at its lower end and adapted to move beneath a pin connected to the lower section, these levers connected by curved links pivoted to each, whereby the movement of the upper lever operates to fold 95 100

or open the sections, the curved links acting as braces to lock the parts when opened in line, substantially as shown and described.

2. A folding step comprising two similar sections hinged together in the rear, a lever pivoted to the upper section, a similar lever provided with a slot having a locking-offset at the top and adapted to move along the line of its slot beneath a headed pin in the lower section, curved braces pivoted to and connecting such levers above and below, and a locking-plate connected to the upper curved brace, having a spring-pin for entering a notch in the upper lever, the sides of the step-frame connected by a rod passing through them, its squared ends entering an opening on one side in the lower brace and on the opposite side in a lock-plate provided with a similar offset or slot, whereby the action of the lever is transmitted through the frame to lock the lower section of the steps on both sides simultaneously, substantially as shown and described.

3. A folding step comprising an operating-

lever pivoted to the upper section, a similar lever slotted at its lower end to move beneath the head of a pin driven into the lower section, the upper and lower levers connected by curved braces, a rod passing through the sides of the upper section behind the hinge, its end squared to prevent its independent revolution, a lock-plate on the opposite side of the frame connected to such rod and provided with a slot for traversing a pin driven into the lower section, and offsets provided in the slots of such plate and of the opposite lever, whereby the movement of the upper lever operates to lock both sides of the device when the lower section is let down, all combined substantially as shown and described. 25

Correction in Letters Patent No. 446,385.

It is hereby certified that in Letters Patent No. 446,385, granted February 10, 1891, upon the application of John S. Jordan and James E. Eller, of Indianapolis, Indiana, for an improvement in "Folding-Steps," an error appears in the printed specification requiring correction, as follows: In line 94, page 1, the word "tubular" should read *similar*; and that the Letters Patent should be read with this correction therein that the same may conform to the record of the case in the Patent Office.

Signed, countersigned, and sealed this 17th day of March, A. D. 1891.

[SEAL.]

CYRUS BUSSEY,
Assistant Secretary of the Interior.

Countersigned:

C. E. MITCHELL,
Commissioner of Patents.
